UNITED STATES PATENT OFFICE.

MOSES NICHOLLS, OF OTTUMWA, IOWA, ASSIGNOR TO MARTIN HARDSCOG
AND EMMET A. WORK, OF OTTUMWA, IOWA.

MITER-BOX.

SPECIFICATION forming part of Letters Patent No. 738,930, dated September 15, 1903.

Application filed August 30, 1902. Serial No. 121,630. (No model.)

To all whom it may concern:

Be it known that I, MOSES NICHOLLS, a citizen of the United States, residing at Ottumwa, in the county of Wapello and State of Iowa, 5 have invented a new and useful Miter-Box, of which the following is a specification.

This invention is an improved construction of miter-box, the object being to provide a device which can be quickly and easily set up 10 for use and one which can be quickly and accurately adjusted so as to cut material at any desired angle.

Another object of the invention is to provide a miter-box in connection with which 15 either an ordinary saw or a miter-saw can be used.

Another object is to provide a miter-box which can be quickly and easily taken apart when not in use and packed away, so as to 20 occupy very little space.

With these and certain other objects in view, as will appear hereinafter, the invention consists in the various devices of construction, combination, and arrangement, all of which 25 will be fully described and then pointed out in the claims.

In the drawings forming a part of this specification, Figure 1 is a perspective view of a miter-box constructed in accordance with my 30 invention and showing the practical application thereof. Fig. 2 is a side view of the same. Fig. 3 is a detail view showing the manner of connecting the graduated segment to the forwardly-projecting arms. Fig. 4 is a top plan view. Fig. 5 is a detail perspective view of the back plate and one of the forwardly-projecting arms and a portion of the graduated segment. Fig. 6 is a detail perspective view of one of the guides. Fig. 40 7 is a detail perspective view of the detachable frame adapted for use in connection with an ordinary handsaw. Fig. 8 is a perspective view of the rear end of a lever, illustrating the manner of connecting it to the lower end 45 of the tubular post. Fig. 9 is a cross-section at left end of Fig. 1.

In the practical embodiment of my invention I employ a back plate A, which may be constructed from any desirable material and 50 made of any size and shape desired. This back plate A has a central vertical opening

A', at the bottom of which is arranged a bearing A², the purpose of which will appear hereinafter. The front face of the plate A is grooved vertically, as shown at A³, in order 55 to afford a firm grip upon the material to be cut, and the rear face is preferably constructed with reinforcement-ribs A⁴ to give the side plates the proper strength. The plate is preferably constructed with end extensions A⁵, which are in the same vertical plane as the plate A, and extending forwardly and horizontally from the ends of these extensions are the arms A⁶, preferably integral with the said back plate and extensions, the forward 60 ends of said arms being turned upwardly, as shown at A⁷, and carrying the bind-screws A⁸, by means of which the miter-box is clamped to a piece of material which virtually constitutes the bottom of the miter-box, said piece 65 of material resting upon the forwardly-extending arms A⁶ and clamped against the plate A and its extensions A⁵ by means of the said screws A⁸. A graduated segment B connects the forwardly-projecting arms A⁶, said 70 arms being formed with lugs A⁹, to which the reduced ends of the segment B are secured. The graduations are marked upon the upper 75 face of the segment B, as indicated at B', and these graduations may be arranged according to any desired scale, so that, if desired, fractional portions of angles may be cut.

A post C, reduced at its lower end, as shown at C², is journaled in the bearing A², said post being tubular in form and slotted vertically, as shown at C', and occupies the central vertical opening A', produced in the back plate A. The hand-lever D, bifurcated at its rear end, as shown at D', is securely fastened upon the downwardly-projecting end 85 C² of the post C, a clamping-screw D², binding the bifurcated end of said lever securely upon said depending end. This hand-lever 90 D projects forwardly beyond the curved segment and rests upon the upper face thereof, 95 as most clearly shown in Figs. 1, 2, and 4, and by moving the said hand-lever to either the right or left the tubular post C is turned correspondingly to the right or the left. The hand-lever D carries a tubular post E, similar in construction to the tubular post C— 100 that is, it is slotted vertically, as shown at

E'—and working in these tubular posts C and E are the saw-guides F and G, respectively, said guides having head portions F' and G', provided with openings F² and G², which terminate in vertical slots F³ and G³, respectively. These slots F³ and G³ are adapted to register with the slots C' and E' and are intended to receive the body or blade of the saw, while the openings F² and G² are intended to receive the back of the ordinary miter-saw or the detachable frame which I have devised for use in connection with an ordinary handsaw and which will hereinafter be fully described. Thus it will be seen that when the saw is arranged in the guides and the said guides properly set in the tubular slotted posts the saw can be quickly and easily adjusted to the desired angle by shifting the hand-lever along the graduated segment. In order to lock the said hand-lever in its adjusted position, I employ a locking-catch H, which is pivoted in a depending bracket H', extending downwardly from the hand-lever D, and the said catch has an eccentric head H², which binds against the under side of the segment B when the forward end H³ of the said catch is thrown down, and in order to normally hold the said forward end in its downwardly-projecting position I employ a spiral spring H⁴, which bears upon the under side of the lever D and upon the upper side of the catch and surrounds the guide-post H⁵, carried by the said latch. When it is desired to disengage the locking-head from the segment, it is only necessary to press upwardly upon the end H³. The hand-lever can then be moved to the right or left until the proper adjustment has been secured, and then by releasing the catch the spring will immediately bind the said head to the segment and lock the catch in its proper position.

As before stated, the guides F and G are constructed to receive an ordinary miter-saw; but in case should it be desired to use an ordinary handsaw in connection with my improved construction of miter-box I have devised a detachable frame which can be connected to the blade or body portion of an ordinary handsaw and which will then enable the said saw to be used in connection with my miter-box and will secure as accurate an adjustment and operation as a miter-saw, having the back rigidly and permanently connected to the said blade. This detachable frame I have shown applied to the saw in Fig. 1, and in Fig. 7 I have shown the said frame detached, and while various constructions might be employed I prefer to construct the said frame I and the bar I', to the rearward end of which are connected the parallel members I², binding-screws being arranged at the upper and lower ends of said parallel members. The forward end of the bar I' is curved downwardly, as shown, and connected thereto are the parallel members I³, said mem-

bers being provided with clamping-screws, so that the plate of the saw can be securely clamped between the parallel members I² and I³, and the bar I' will then constitute the back of the saw-frame, which will occupy the openings F² and G² of the guides. It will thus be seen that the saw K, used in connection with my miter-box, can be either a miter-saw or an ordinary handsaw.

L indicates a bracket carrying an eccentric lever L', by means of which a block can be clamped upon the strip of material constituting the bottom of the miter-box, which block will serve as a stop and gage to limit the length of the material to be cut.

M designates an extension-back, formed of a yoke crossing beneath the removable base and extending upward at the front and rear of said base. The rear arm of the yoke M is almost as high as the back A and serves as a back-support for the portion of material being cut which extends materially beyond the back A, and the front arm of the yoke is provided with a set-screw M² for binding engagement with the front margin of the base. The yoke may be moved longitudinally of and fixed in any desired position on the removable base. It will be understood, however, that these appliances are not absolutely necessary for the proper manipulation of the improved construction of miter-box.

In order to use the box, it is only necessary to clamp the same to a piece of material, place the saw in the guides, and then arrange the guides in their tubular posts. By moving the hand-lever the saw can be adjusted to the proper angle. When it is desired to pack the miter-box away, it is only necessary to remove the saw, unclamp the box from the board or piece of material, and disconnect the hand-lever from the depending end post C.

It will thus be seen that I provide an exceedingly simple and efficient construction of miter-box capable of carrying out all the objects hereinbefore mentioned.

Having thus fully described my invention, what I claim as new, and desire to secure by Letters Patent of the United States, is—

1. A miter-box comprising a back plate, the graduated segment, clamping means arranged for engagement with a removable base at the ends of said segment, a hand-lever movable upon the segment and the saw-guides carried by the said hand-lever.

2. A miter-box comprising a back plate having forwardly-projecting arms carrying clamps shaped for engagement with a removable base, a segment connecting said arms, the hand-lever, tubular posts and the guides carried therein.

3. A miter-box comprising a back plate having forwardly-projecting arms, clamping means shaped for engagement with a removable base, parts of said clamping means on the back plate and parts on the extremities of the projecting arms, a segment connecting

the said arms, the hand-lever, the tubular slotted posts, the slotted guides, and means for locking the said hand-lever.

4. In a miter-box, the combination of a back plate having forwardly-projecting arms, carrying clamps shaped for engagement with a removable base, a segment connecting said arms, a hand-lever, posts and guides therein carried by said hand-lever and extension backs removably, replaceably and adjustably mounted on said removable base, whereby the back-support of material being sawed in said miter-box may be extended laterally of the back plate.

5. In a miter-box, a saw-guide attachment, comprising the base, formed with a vertical back plate, a segmental graduated front plate and end bars connecting said plates, clamps on said base and arranged to engage and support a block, which block forms the bottom of the box, an arm pivoted at one end on the rear portion of said base and crossing the

segmental graduated plate, and saw-carrying posts carried by said pivoted arm.

6. In a miter-box, a back plate having forwardly-projecting arms, carrying clamps shaped for engagement with a removable base, a segment connecting said arms, a hand-lever pivoted at one end on the rear portion of said back plate and crossing said segment, tubular posts carried by said hand-lever, guides carried by said posts, a fulcrum projecting from said hand-lever to a point below said segment, a latch pivoted on said fulcrum and having a curved end portion eccentric to its pivot and arranged for engagement with the lower face of said segment and a spring interposed between and impinging the extremities of said hand-lever and latch.

MOSES NICHOLLS.
